(57) **CLAIM**

The ornamental design for a scooter, as shown and described.

DESCRIPTION

FIG. 1 is a perspective view of a scooter showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged partial view of handlebars taken from the top of FIG. 1;

FIG. 10 is an enlarged partial view of the scooter taken from the left side of FIG. 1;

FIG. 11 is an enlarged partial view of the scooter taken from the bottom-middle of FIG. 1;

FIG. 12 is an enlarged partial view of handlebars taken from the top of FIG. 2;

FIG. 13 is an enlarged partial view of the scooter taken from the bottom left of FIG. 2;

FIG. 14 is an enlarged partial view of handlebars taken from the top of FIG. 3; and,

FIG. 15 is an enlarged partial view of handlebars taken from the top of FIG. 4.

The broken lines in the drawings depict portions of the scooter that form no part of the claimed design.

The dash-dot broken lines represent the boundaries of the enlarged partial views of FIGS. 9-15 and form no part of the claimed design.
